UNITED STATES PATENT OFFICE.

JAMES A. HORTON, OF WORCESTER, MASSACHUSETTS.

WIRE-DRAWING MACHINE.

Application filed December 23, 1922. Serial No. 608,714.

This invention relates to the drawing of steel or other metallic wire by what is known as the continuous process, through a number of dies, and by a series of drums, in one operation. The invention is designed to overcome certain objectionable features of previous machines, viz, the revolving of the drawing drums at a peripheral speed greater than the travel of the wire, causing the wire to be chafed and the lubricating material to be removed from that portion of the wire which comes in contact with the drawing drums.

The dies are made usually of steel or chilled cast-iron. Wire drawn through these dies has to be coated with a suitable lubricating material, which should remain on the wire in its passage through the dies.

The coarser wires are usually drawn dry, and are coated with lime and soap, or lime and tallow, as a lubricator. The finer sizes are usually drawn wet, or liquor drawn, and usually coated with copper or copper and tin. If a small strip of coating is removed by the slippage of the wire on the drums, the steel of the wire will come into contact with the steel of the die, and as there are several drums, there will be several such removals of coating. When the wire comes in direct contact with the material of the dies, it is scratched by such direct contact, for want of the coating. To avoid this scratching I have devised the improved machine hereinafter described.

Of the accompanying drawings forming a part of this specification,—

Figure 1 is a front elevation of a machine embodying the invention.

Figure 2 is a plan view, showing a motor drive.

Figure 3 is a section on line 3—3 of Figure 1.

Figure 4 is a section on line 4—4 of Figure 1.

Figure 5 is a section on line 5—5 of Figure 1.

Figure 6 is a right hand end elevation.

Figure 7 is an enlargement of a portion of Figures 5 and 6.

Figure 8 is a front elevation of the parts shown in Figure 7.

Figure 9 shows the planetary locking device.

Figure 10 shows the sun and internal

gears, with the planet gears in place, and the pockets into which enter the locking pin hereinafter described.

Figure 11 is a front elevation, showing a modified form of the machine, the shafts being in an upright position, and the means of driving employed when an electric motor is not available.

Figure 12 is a plan view of the form of machine shown by Figure 11.

The same reference characters indicate the same parts in all the figures.

In the drawings, 15 represents a frame, which may be of any suitable form, and adapted to support the usual drawing drum shafts hereinafter described, and an inverted drum adapted to discharge its coil downward.

16 represents the first drawing-drum, 17 the second drawing-drum, 18 the third drawing-drum, and 19 the inverted finishing drum.

20 represents an idler sheave, which guides the wire passing from the first to the second drum. 21 represents the holder of the first and second dies; 22 the holder of the third die; and 23 the holder of the fourth die; 24 represents the shaft on which are fixed the second drum 17, and a gear 25 (Figure 5). 26 (Figure 5) represents a sleeve on which the drum 16 and gear 28 are fixed, the sleeve being rotatably mounted on the shaft 24. 29 represents a sleeve rotatably mounted on a shaft 27 (Figure 5). On one end of the sleeve 29 is fixed a pinion 30, meshing with the gear 28, and on the other end of the sleeve is fixed a sun gear 31. A sleeve 32 is mounted loosely on the sleeve 29. To the sleeve 32 is fixed a pinion 33, and an internal gear 34, the pinion 33 meshing with the gear 25. To the shaft 27 is fixed a planet-carrying gear 35.

The shafts 24 and 27 are mounted in suitable bearings in the frame 15.

Movable in the shaft 27 is a rod 36 (Fig. 5), adapted to be moved outward by a spring 37, and to be pushed inward by means including a cam 38, fixed to a shaft 39, which is mounted in suitable bearings 40, and a lever 41 fulcrumed at 42, and actuated by the cam 38 to push the rod 36 inward against the force of the spring 37. A lever 43 fulcrumed at 43^a, on the gear 35, carries a pin 44, which, when moved by the spring

37, through the rod 36, engages one of a circular series of pockets 31^a (Figure 10) in the gear 31.

A lever 45 (Figure 6) fixed to the shaft 39, has its other end supported by a link 46, hanging on the wire being drawn, near the first die-holder. The shaft 39 is further provided with two cams 38^a and 38^b similar to the cam 38 and cooperating, respectively, with levers 68 and 90, hereinafter referred to. When the link 46 is not supported by the wire being drawn, the lever 45 will fall to the position represented by dotted lines in Figure 6, rocking the shaft 39 and causing the several cams, 38, 38^a, 38^b, thereon to actuate their coacting levers 41, 68 and 90 and the clutch mechanisms controlled thereby. 47, 48, 49 represent planet gears mounted to rotate loosely on studs carried by the gear 35 (Figure 10).

As shown by Figure 3, the drawing-drum 18, and a gear 50, are fixed to a shaft 51, mounted in suitable bearings in the frame. Fixed to a loose sleeve 52, mounted on the shaft 51, are bevel gear 53 and gear 54. The gear 53 meshes with a bevel gear 55, which is fixed to a shaft 56. A pinion 57 is fixed to the shaft 56, and meshes with a gear 58 (Figure 2), which meshes with a gear 59, fixed to the finishing drum 19.

The gear 54 meshes with a pinion 54^a on a sleeve 32^a, which in turn is mounted on a sleeve 29^a on a shaft 27^a. To the sleeve 32^a is also secured an internal gear 72 and on the sleeve 29^a within said internal gear is a second sun gear 31^a. A planet-carrying gear 65 fixed to the shaft 27^a is adapted to be connected by a clutch pin 44^a with the sun gear 31^a, said clutch pin being actuated by a spring pressed rod and lever 90 cooperating with a cam 38^b on the shaft 39 in the same manner as the clutch 44 is operated by the lever 41 and cam 38.

The field 10 of an electric motor (Figure 4) is mounted in a fixed frame 60. A gear 61 is fixed to the shaft 62 of the armature 60^a of the motor, and meshes through an intermediate gear 61^a (Figure 1) with the carrier gear 35 (Figure 1). A gear 63 is fixed to the extension 64 of the field portion of the motor, and meshes with a carrier gear 65 (Figures 2 and 3).

A shaft 66 (Figure 4) is mounted in suitable bearings in the frame. Inserted in the shaft 66 is a rod 67, pressed outward by a spring 71, and inward through a lever 68, actuated through the cam 38^a, on shaft 39. A gear 69 is fixed to the shaft 66, and meshes with the planet-carrying gear 65 (Figures 1 and 3). A gear 70, mounted on the shaft 66, and free to revolve or slide thereon, meshes with the planet-carrying gear 35. Clutch members 69^a and 70^a in gears 69 and 70, are adapted to engage each other when the spring 71 is liberated, the clutch mem-

bers locking the two members of the motor to a fixed speed performing the same function as 37 and 67, are released.

Operation.

70

With the lever 45 resting in the position shown by the dotted line (Figure 6), the shaft 39 will have been partially rotated and the cams 38, 38^a, 38^b, will have released the levers 41, 68 and 90 and permitted the springs cooperating with said levers to force the locking pins 44, 44^a, into the pockets of the sun gears, thus locking the planetary systems to revolve as one gear. The spring 71 will also force the gears 69, 70, into clutched position, thus causing the two members of the motor to revolve at equal speeds. The only function of the gears 69, 70, is to fix the speed of each member of the motor when the drums are driven at fixed speeds relative to the motor speeds. The particular motor shown comprises a motor field mounted to revolve in suitable bearings and having the pinion 63 connected thereto and engaging one of the planetary systems of gearing included in the machine. The armature of the motor revolves inside the field as usual, and has a pinion 61 connected to its shaft, which pinion drives the other planetary system. The balancing of the load upon the motor and armature is brought about by the strain on the wire in excess of that required to draw it through the die due to inequalities of the die as originally made or to uneven wear. The wear between the first two dies is compensated for by the first planetary system which, as before noted, is driven by the pinion 61 on the armature shaft. The strain produced by the second and third dies is compensated by the second planetary system which is driven by the pinion 63 connected to the motor field. The compensating effect of the motor parts due to the elasticity of the current compensates for the variation of each pair of dies so that the speeds will all be automatically adjusted by the excess strain on the wire. For example, a wire of No. 8 gage will break under a strain of approximately 1800 lbs., while a strain of about 1200 lbs. will be sufficient to draw a No. 5 rod through a No. 8 gage die. The speed of the motor parts will be varied by a difference of say 100 lbs. between the two planetary systems so that the speeds of all the several drums will be automatically adjusted. When the wire has passed through the first die, the first planetary system is relieved of the strain of driving the drum 16 and would instantly speed up if the dropping of the lever 45 did not effect the locking of the two planetary systems to the motor members as described, and thus fix the speeds of all the drums.

A wire rod is threaded through the first die, is carried in several wraps around the 120

125

130

first drum 16. The wire is then passed back around the idler sheave 20, and through the second die, then carried in several wraps around the second drum 17, and then to the 5 third die, then in several wraps around the third drum 18, and then through the fourth die to the inverted finishing drum 19. The link 46 on the lever 45 is now engaged with the wire as it leaves the first die, and the machine is in full operation, and continues 10 to operate until the wire is finished at the first die, and releases the link 46, the lever 45 immediately drops to the position shown by dotted lines, Figure 6 and locks the compensating system to drive the drums at a 15 fixed predetermined speed, to finish the wire remaining on the drums.

In using an upright drum with all the 20 spindles in an upright position, as shown by Figures 11 and 12, the idler sheave 20 is dispensed with, and the operation is as follows:

A wire rod (Figure 11) is passed through 25 the first die and carried in several wraps around the first drum 16^a (Figure 11), then through the second die, and carried in several wraps around the second drum 17^a, then back through the third die, and carried around the drum 18^a in several wraps, then 30 through the fourth die to the finishing drum 19^a.

The dies are of a predetermined size or 35 gauge, but in the process of making the eyes of these dies, the size of the eyes is not always of the exact size called for, and may vary slightly. Sometimes the eye is intentionally varied to suit a particular kind of rod.

This variation affects the elongation of the 40 wire to an appreciable extent, hence the predetermined speed of the drawing drums cannot be fixed to match the elongation.

The main object of this invention is to so 45 construct a machine for continuous drawing, that there will be no slip of wire on the drawing drums, because all the drums will automatically adjust themselves to the call and tension of the wire. This I accomplish 50 by using the planetary gearing in combination with any suitable power (Figures 11 and 12), or in combination with an electric motor of special construction, in which both members of the motor are adapted to revolve, although in opposite directions, thus using 55 the elasticity of the electric current as a compensating element of the machine. When the electric current is not suitable or convenient, I employ an additional planetary gearing, and drive it by power from any 60 convenient source.

In using the upright drum, with all the 65 spindles in an upright position, power is applied from any suitable source, to the pulley P, (Figure 12), mounted on a suitable shaft 74, to which is fixed a bevel gear

75, which meshes with the beveled planet carrier gear 76, of the planetary system used in place of the special motor as shown in Figure 2.

Another object is to provide a means of 70 locking all the compensating parts, including the motor, so they will revolve at a fixed predetermined speed, when some, but not all of the drums are drawing, to prevent any drum which becomes unloaded from revolving at a higher rate of speed, due to the unbalancing of pull on the different drums. 75

Another object is to cause the drums to revolve at a fixed predetermined speed during the threading operation. I prefer to 80 use an inverted drum for a finishing drum, but an upright drum 19^a (not inverted) may be used with all the compensating mechanism, as shown in Figures 11 and 12, the drums being driven from any source of 85 power.

Another object is to provide a means of 90 automatically controlling the locking through the action of the wire at the first die.

I claim:

1. In a continuous wire-drawing machine, 95 two dies, two drums driven through planetary gearing, two other dies, two other drums, driven by other planetary gears, and an electric motor, comprising two members both of which are adapted to revolve, one member driving one planetary system, and the other member driving the other planetary system, whereby all the drums are in 100 one compensating system.

2. In a continuous wire-drawing machine, 105 two dies, two drums, a planetary system for driving both said drums, two other dies, two other drums, another planetary system for driving the last said drums, a third planetary system between the first two, means for carrying the planetary gears of the third system, and means for locking the members 110 of each of the planetary systems, whereby all the drums will be positively driven at predetermined different speeds.

3. In a continuous wire-drawing machine, 115 two dies, two drums, means for revolving the drums, an indicating lever adapted to be supported by the wire at the first die, while holding the compensating systems in an operative system, and to lock them all when the wire fails to support the lever.

4. In a continuous wire-drawing machine, 120 two compensating planetary systems, two planet carriers, and an electric motor, with the field and armature revolving in opposite directions, one planet carrier revolved by the armature, and the other revolved by the field 125 of said motor.

5. In a continuous wire-drawing machine, 130 two dies, two drums driven through a planetary system, two other dies, two other drums driven through another planetary system, a

motor with armature and field, both adapted to revolve at the same or different speeds, and means whereby the two motor members are automatically caused to revolve at a fixed predetermined speed of each member.

6. In a continuous wire-drawing machine, two dies, two drums driven through a planetary system including a sun gear and an internal gear, a gear fixed to each drum, a gear fixed to the sun gear, a gear fixed to the internal gear, a planet-carrying gear, two other dies, two other drums driven through a second planetary system, a gear fixed to each drum, a gear fixed to the internal gear of the second system, a planet-carrying gear for the second system, a third planetary system adapted to drive the first and second systems, and means whereby the

sun gear and internal gear of the third system are revolved at the same speed while all the drums revolve at a different predetermined speed.

7. In a continuous wire-drawing machine, two dies, two drums, an electric motor, of which the armature and field are adapted to revolve; two planetary systems, one driven by the armature and one driven by the field; and means for automatically locking the two members of the motor to a fixed predetermined speed when one member becomes partly unloaded by the passage of the wire being drawn, from the first die.

In testimony whereof I have affixed my signature.

JAMES A. HORTON.
